US00D696910S

(12) **United States Design Patent**
Franczyk et al.

(10) **Patent No.:** **US D696,910 S**
(b4) **Date of Patent:** ** **Jan. 7, 2014**

(54) **FOOD CONTAINER**

(75) Inventors: **Erin Franczyk**, Naperville, IL (US);
Robert Michael Grennan, Naperville, IL (US); **Miguel Cano**, Chicago, IL (US)

(73) Assignee: **Goodbyn, LLC**, Naperville, IL (US)

(**) Term: **14 Years**

(21) Appl. No.: **29/415,430**

(22) Filed: **Mar. 9, 2012**

(51) **LOC (10) Cl.** **07-01**

(52) **U.S. Cl.** **D7/629**
USPC **D7/629**

(57) **CLAIM**

The ornamental design for a food container, as shown and described.

DESCRIPTION

FIG. 1 is a top perspective view of a food container showing our new design;

FIG. 2 is a bottom perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof; and,

FIG. 8 is a right side elevational view thereof.

1 Claim, 6 Drawing Sheets
